UNITED STATES PATENT OFFICE.

ROBERT KNOX BARNETT, OF PHILADELPHIA, PENNSYLVANIA.

ELEVATOR CONVEYER.

Application filed September 9, 1920. Serial No. 409,045.

To all whom it may concern:

Be it known that I, ROBERT KNOX BARNETT, a citizen of the United States, residing in Philadelphia, Pennsylvania, have invented Elevator Conveyers, of which the following is a specification.

This invention relates to elevating conveyers which include automatic devices for causing discharge or delivery of the articles carried, one of my objects being to provide a relatively simple, and substantial means whereby the contents of a tray, bucket or other conveying element shall be caused to be automatically delivered therefrom at a predetermined point or at any one of a number of such points.

I further desire to provide a novel combination of conveying elements with one or more movably supported receiving troughs or platforms of novel construction and mounting, designed to be automatically shifted by said elements to permit of their passage and thereafter automatically returned to their normal positions in which they can receive the contents of the conveying elements if these should be discharged.

Another object of my invention is to provide novel means for tripping the conveying elements or load carriers of an elevator conveyer, together with a novel form and mounting of receiving structure for the articles delivered from said carriers;—the invention contemplating also a novel device for controlling from a distance the action of the tripping means.

These objects and other advantageous ends I attain as hereinafter set forth, reference being had to the accompanying drawings, in which,

40 Figs. 1 and 2 are respectively a vertical section and a front elevation to some extent diagrammatic, illustrating an elevator conveyer made in accordance with my invention;

45 Fig. 3 is a horizontal section on the line 3—3, Fig. 1;

Fig. 4 is a perspective view on a scale larger than that of Figs. 1 to 3, illustrating the detail construction of one of the conveying trays and a receiving trough with certain of their associated parts, constructed in accordance with my invention; and

50 Fig. 5 is a diagrammatic view of a modification of my invention, illustrating a combination of parts for controlling the tripping cams from a distance.

In the above drawings, 1—1 represent two parallel endless chains which are suspended from and actuated by a pair of sprocket wheels 2—2 mounted on a shaft 3 60 driven from an electric motor 4 or other suitable source of power. Said sprockets with the motor and their associated parts are preferably mounted on a frame work 5 at the top or upper part of the building or 65 other structure in which the elevator is mounted, and in the present instance I have shown such a structure as having three floors 6, 7 and 8.

Adjacent the lowest floor the chains 1—1 70 pass around two sets of idler sprockets or guide pulleys 9 and 10 whereby their direction is changed from vertical to horizontal, and there is also an adjustable pair of bottom sprockets 11 for one end of the horizontal runs of the two chains. Mounted on and carried by the two chains 1—1 are a suitable number of conveying elements 12 in the form of trays, buckets or carriers pivotally supported so as to be capable of being swung 80 out of their normal positions and caused to discharge their contents.

A loading platform 13 or equivalent structure is arranged over the upper of the horizontal runs of the chain 1—1, and the elevator shaft or well has at opposite sides vertically extending tracks or guides 14 for the chains. Said shaft in addition is preferably provided with enclosing walls 15—15 and a central vertically extending partition or 90 frame 16 whereby the two vertical runs of chain with their ascending and descending carriers are separated and the said carriers incidentally prevented from tipping except at such points as the walls and partitions 95 are or may be cut away.

Each of the trays or conveying elements 12 is provided with a pair of projecting members in the form of arms 17, extending in opposite directions from each of its sides 100 adjacent the pivots connecting it to or suspending it from the two chains 1—1, and in one form of my invention I provide pairs of tripping cams 18 which may be bolted or otherwise rigidly fixed to the guides 14 adjacent openings into the elevator shaft, whereby the projecting arms 17 of each tray are engaged and the latter caused to swing on its pivots into such a position as to cause its load to be discharged by gravity. These 105 pairs of tripping cams 18 are so positioned relative to the floors 6 or 7 and to the open-

ings in the wall of the elevator shaft as to permit of the mounting under them on said floor a package or load-receiving platform 19 having a receiving extension 20 pivotally connected to it as by a shaft or spindle 21, and extending into the elevator shaft or well in such position as to be engaged by the conveying elements 12 as these move upwardly.

Each of said extensions 20 has arms 22 projecting under the body of the receiving platform 19 and normally engaging a pair of abutments 23 so placed as to normally hold the extension in an inclined position with its top surface substantially in the plane of the top or inclined surface of the body of the receiving platform 19. Said extensions are thus each free to be swung upwardly about their spindles 21 as axes in order to permit of the passage of successive conveyer elements or carriers 12 without causing the latter to be swung on their pivots. Springs 24 are connected between the arms 22 and the adjacent parts of the body of the platform 19, so that after being displaced from their normal positions shown in Fig. 4, the platform extensions are returned to and maintained in such positions.

The tripping cams of that pair which it is desired shall act upon the carriers to cause delivery of their contents at any particular floor are arranged as shown in Fig. 4, at such positions on the guide tracks 14 that each carrier is permitted to pass the adjacent extension 20 before its arms 17 are acted on by said cams. There will thus be no possibility of the articles being delivered from any carriers before the platform extension 20 has returned into such a position as to receive the same and permit of their sliding onto the main portion of the receiving platform or chute 19.

In that form of my invention shown in Figs. 1 to 4 inclusive, each of the tripping cam structures consists of a casting 26 bolted or riveted to the guides or tracks 14 and having the cam 18 carried by an elongated block 27 pivoted to said casting by a bolt or pin 28, so as to permit said block being swung to cause the cam to move into and out of the path of movement of the tripping arms 17 of the carriers or conveying elements. Holes are formed in each of said castings 26 for the reception of a pin 25 which may be passed through either of two holes in its particular cam block to retain it either in position to engage the carrier arms when this is desired, or to retain it in such position that it will not engage said arms.

Under conditions of operation, the pair 60 of chains with their conveying elements or trays 12 are driven by the motor 4 and articles to be conveyed to the floor 7 for example are delivered from the platform 13 onto said carriers as these are moved by said 65 chains through their upper horizontal

run. Upon reaching the extension 20 of the first receiving platform which is located on the floor 7, each carrier engages and swings said extension up and outwardly without being affected thereby. Immediately after the passage of said carrier, gravity and the springs 24 return the extension to its normal position in which it projects into the elevator well or casing. Thereupon the arms 17 of the carrier come into engagement with the blocks of the tripping cams 18 adjacent the opening in the elevator shaft and, by swinging said carrier on its supporting pivots, causes the article thereon to be delivered first to the extension 20 and then to the receiving platform or chute 19 from which it falls onto the floor 7.

After passing out of engagement with this first pair of tripping cams, the carrier resumes its normal position and continues to move upwardly with the chains to which it is attached, thereafter similarly engaging and swinging the extension 20 of the receiving platform 19 of the floor 6. Inasmuch however as the blocks of the tripping cams adjacent this second receiving platform are in their outer or inoperative positions, there is no swinging of the carrier on its pivots, and after those portions of the chains to which it is attached pass over the top 95 sprockets 2 it moves down in the descending portion of the elevator shaft.

If desired, chutes or platforms 30 may be provided at each of the floors 6 and 7 adjacent the descending run of the elevator so as to permit of articles being delivered to the carriers as they pass downwardly therein and afterward conveyed to and discharged on some other floor by the means above described.

Under certain conditions I may provide means for controlling the positions of the tripping cams 18 from a distance, and for this purpose I may employ a tripping block connected to the movable core 31 of an electromagnetic winding or solenoid 32 (Fig. 5). By means of a spring 33 the tripping cam block is normally maintained out of the path of the carrier arms 17 but when by the energization of a suitable electric circuit connected to said winding, the latter is energized, the core 31 is drawn into such position as to project the block, causing it to be struck by the arms 17 with a resulting tipping or swinging of the carriers connected thereto and the discharge of the article thereon.

By the above described arrangement of parts not only am I enabled to determine the point at which the articles carried by the conveying elements shall be discharged, but by providing the receiving platforms or chutes made as described, I prevent the possibility of any of the articles accidentally falling into the elevator chute after delivery.

ery from their trays and cause them to be discharged and finally come to rest at some distance away from the elevator.

I claim:

5 The combination in an elevator conveyer of a series of pivotally mounted conveying elements; a receiving member having an ex-

tension normally projecting into the path of said elements and movable thereby to permit their passage; with a cam adjustable at 10 will into and out of the path of movement of said conveying elements for tripping them after they have passed said extension.

ROBERT KNOX BARNETT.
